CRUCIFIX FOR A ROSARY

Leopold Quirion, Sherbrooke, Quebec, Canada
Application September 8, 1955, Serial No. 37,849

Term of patent 14 years
(Cl. D45—17)

Fig. 1

Fig. 2

Fig. 3

Figures 3 and 4 are sections on line 3—3 and 4—4 of Figure 1.

I claim:

The ornamental design for a crucifix for a rosary, as shown.
